[57] CLAIM

The ornamental design for a bunged drum or the like, as shown and described.

DESCRIPTION

FIG. 1 is a top, front perspective view of a bunged drum or the like showing my new design;

FIG. 2 is a side elevational view thereof, on a slightly reduced scale, the opposite side being the same in appearance.

FIG. 3 is a top plan view, and

FIG. 4 is a bottom plan view.

FIG.1

FIG.2

FIG.3

FIG.4
